UNITED STATES PATENT OFFICE.

BELFORD G. ROYAL, OF CAMDEN, NEW JERSEY, ASSIGNOR TO VICTOR TALKING MACHINE COMPANY, A CORPORATION OF NEW JERSEY.

TALKING-MACHINE.

1,305,745.

Specification of Letters Patent. Patented June 3, 1919.

Application filed January 22, 1910, Serial No. 538,594. Renewed October 16, 1918. Serial No. 258,484.

To all whom it may concern:

Be it known that I, BELFORD G. ROYAL, a citizen of the United States, and a resident of the city of Camden, State of New Jersey, have invented certain new and useful Improvements in Talking-Machines, of which the following is a full, clear, and complete disclosure.

My invention relates to that type of sound recording or reproducing machines in which the record support is given a constantly increasing or decreasing angular velocity, in order that that portion of the spiral record groove directly under the stylus of the recorder or reproducer may be given a constant linear velocity, and my invention particularly relates to the mechanism for operating the record support in the manner above referred to.

The object of my invention is to construct a sound recording or reproducing machine which can be interchangeably used to record or reproduce sounds from records which are to be rotated at a constant angular velocity and from those to be rotated at a variable angular velocity; and which machine can be readily and easily controlled and adjusted for use with either of said types of record, to provide a mechanism for varying the speed of the motor so as to produce the desired variable speed of the record support, which mechanism shall be automatic in its action and independent of the reproducer itself; and to provide a device which is simple and easy of manipulation and adjustment.

For the purpose of explaining the manner in which my invention may be carried out in practice, I have shown in the drawings a sound reproducing machine provided with my means for operating the same with both types of records above referred to, but my invention is not to be construed as being limited to a sound reproducing machine as it is equally adaptable for use in recording machines.

In talking machines or sound reproducing machines of the type in which the record is in the form of a disk, having therein a spiral groove the convolutions of which begin at or near the periphery of the disk and terminate at a point near the center of the disk, and in which during the reproduction of sound therefrom the reproducer is carried inwardly from the periphery of the disk toward the center, by reason of the engagement of the

stylus with the record groove, it is apparent that, with a fixed angular velocity of the record support, the linear velocity of each convolution will decrease in a fixed ratio from the outer to the inner convolution of the record groove and the invention of this application then relates to the providing of a mechanism, whereby the speed of the record as it moves under the stylus may be made constant at the point of its engagement with the stylus, and to do this the mechanism described below is provided to counteract the decrease in the linear velocity of the groove by imparting to the record support a constantly increasing angular velocity, and the rate of the increase in speed should be inversely proportional to the proportion which the radii of adjacent convolutions of the spiral bear to each other for each revolution of the record support; that is to say, by way of example, when the reproducer has traveled across the record one-half of the distance from the periphery of the disk and the center of the disk or record, the speed should be increased two times to maintain a constant linear speed under the stylus and so proportionally throughout the whole travel of the reproducer across the record. This is accomplished by the cam independent of the reproducer and driven by the motor mechanism as will be described below.

It is obvious that to correctly reproduce the sound from a record in which the record support, and consequently the record mounted thereon, will have this variable speed imparted to it, it will have been necessary to have made the original record upon a recording machine to the support of the surface being recorded of which, was imparted a corresponding variable angular velocity.

My invention has for one of its objects the providing of a talking machine with a mechanism which will enable it to be used with either style of record; that is to say, with records in which the record was originally recorded upon a disk which was revolved at a constant angular velocity, and one in which the record was originally recorded upon a record having a variable angular velocity, the variation being such as to impart a constant linear motion to the record at the point of its engagement with the recording stylus.

In the drawings forming a part of this specification, and in which like reference

characters are used to designate the same parts through various views, Figure 1 is a side elevation of a recording driving mechanism embodying my invention and shown as mounted within a sound-reproducing machine cabinet, which cabinet is shown in section; Fig. 2 is a bottom line view of the same; Fig. 3 is an elevational sectional view of the mechanism shown in Figs. 1 and 2, the said section being taken on the line III—III of Fig. 2; Fig. 4 is a similar sectional elevational view taken from the line IV—IV of Fig. 2; and Fig. 5 is a sectional view of a portion of my device taken from the line V—V of Fig. 2.

Referring now more particularly to Figs. 1 and 2, a motor cabinet 1 may be provided with a top lid or closure 2, from which is suspended a plate 3, upon which the various parts of the motor are mounted, which motor may consist of the usual spring barrel 4, operatively connected to the winding-shaft 5, supported in the bearing-blocks 6—7, mounted upon the plate 3. The winding-shaft 5, may extend, as is usual, to a point adjacent to the opening 8, in the casing 1, for the attachment of a winding crank thereto. The barrel 4 may be mounted in the bearing blocks 6 and 6' or in any other convenient manner.

Connected in any suitable manner with the spring barrel 4, is a gear 9, which meshes with a pinion 10, on the shaft 11, journaled at one end in said bearing-block 6, and on its opposite end in a bearing-block 12, suspended from the plate 3. The shaft 11 also carries a beveled gear 13, meshing with a beveled pinion 14, rigidly connected to the spindle 15, to the top of which is secured a record-support 16. The spindle 15 is also provided with a worm-gear 17, which meshes with and drives a worm 18, on the governor-shaft 19, journaled in suitable bearings 20—21, said governor-shaft being provided with the usual flyballs 22 mounted on springs 23, the ends of said springs being connected respectively, to the collars 24—25 on the governor-shaft 19. As is usual in this type of governor the collar 24 is rigidly secured to the governor-shaft 19, while the collar 25 is loose on the said governor-shaft and is connected to a governor-disk or plate 26, which, by the centrifugal action of the flyballs, is drawn inwardly when the balls rotate, the extent of movement being dependent upon the speed of the rotation of the balls. The spring 27 tends to counterbalance to the desired extent the tendency of the collar 25, and the disk or plate 26 to move inwardly under the action of the said flyballs.

The mechanism for varying the speed of the motor is as follows: Meshing with the pinion 10, is a gear 28, rigidly secured to a shaft 29, mounted in bearing-blocks 30—31,

which may be secured to the plate 3 in any suitable manner. The shaft 29 is also provided with a worm 32, which in turn meshes with a worm-wheel 33, mounted on a shaft 34, which in turn may be manually moved longitudinally in a bearing-block 35, mounted on the plate 3. The shaft 34 has also rigidly secured thereto a cam 36, and the said shaft has an outer bearing 37, which bearing is provided with a dial 38, stationarily secured to said bearing 37. The end of the shaft 34 is provided with a knurled head 39, carrying a pointer 40, said head and pointer being rigidly secured to said shaft 34, and the pointer being adapted to swing over and around the dial 38 when the shaft is drawn outwardly to the position indicated in dotted lines in Fig. 2, and manually turned, by means of the knurled head 39.

As has been previously stated, the shaft 34 is longitudinally movable in its bearings, the extent of the movement being sufficient to move the worm-wheel 33 into and out of engagement with the worm 32, as is plainly indicated in Fig. 2. To hold the shaft 34 in position—that is to say, so that the worm 32 and the worm-wheel 33 are in engagement, a suitable lock may be provided, such as is shown in Fig. 5. In this case the shaft 34 is provided with a groove, 41, while the bearing block 35 is provided with a suitable opening registered with said groove and through which a pin, 42, extends, the end of said pin fitting within the said groove 41 and being normally held in that position by a leaf-spring 43. It will be seen, then, that when the knurled head 39 is grasped and the shaft is forced longitudinally inwardly so that the worm 32 and the worm-wheel 33 engage, said shaft and the parts connected thereto are locked or retained in that position. To bring said worm and worm-wheel out of operative relation, it is merely necessary to draw the knurled head 39, (Fig. 1) outwardly, thereby slipping the groove 41 out from under the pin 42.

Mounted upon a suitable standard, 44, is a lever, 45, the free end of which rests against the surface of the cam 36, and mounted upon the same standard and adjacent to said lever 45 is a brake lever 46. This brake lever 46 extends inwardly to a position adjacent the inner side of the governor-disk or plate 26, and is provided with a suitable pad 47, adapted to engage the said disk or plate 26. The opposite end of said lever is provided with a screw, 48, or other suitable adjusting means, the end of the screw being threaded through the said brake lever 46 and bearing against the lever 45, the end of the screw being held in engagement with the said lever 45 by means of a spring 49, one end of which is attached to said brake lever 46, and the other end of which may be attached to any suit-

able support, such as the bearing-block 35. The said screw 48 may be provided with a suitable lock nut 50, to hold the screw in any desired adjusted position.

5 The casing 1 may be provided with a support or bracket 51, upon which may be mounted the sound-conveying arm 52, pivoted to swing over the record on the pin 53, the outer end of said arm 52 being operatively connected to a sound box or reproducer 54, provided with a stylus 55, shaped to coöperate with the record groove of a record 56, mounted upon the record support 16. In the type of sound reproducing machine illustrated in the drawings of this application, the sound box or reproducer 54 is caused to travel across the face of the record by reason of the engagement of the stylus 55 with the groove of the record 56, said groove having undulations therein corresponding to sound waves, whereby the undulations of the record groove impart a movement of vibration to the stylus bar 57 of the reproducer 54 to reproduce the sounds recorded on the record, and at the same time the groove, being arranged in a spiral on the face of the record 56, causes the reproducer to travel slowly across the face of the record.

The operation of the machine above described is as follows: To reproduce sound from a record upon which the original record was recorded with a constant angular velocity imparted to the master record support, the knurled head 39 is pulled outwardly to the position shown in dotted lines in Fig. 2 so that the worm gear 33 is out of engagement with the worm 32, and the knurl is rotated to bring the pointer 40 opposite the graduation on the dial 38, which indicates the proper speed at which said record should be rotated to give the correct or proper reproduction of sound, and in this position the location of the pad 47 on the end of the lever 46 will be such as to allow the governor to rotate constantly at that speed, and a corresponding constant angular velocity of rotation will be imparted to the record support and the record will be reproduced in the ordinary manner.

60 When, however, a record which was recorded at a variable angular velocity is to be reproduced, the knurled head 39 of the shaft 34 will be turned to bring the pointer 40 opposite the proper indication on the dial 38 and to present the corresponding peripheral region of the cam 36 against the side of the lever 45; the brake lever 46 having been so adjusted with respect to the lever 45, or the graduations on the dial 38, that the velocity of the record support will give the proper linear speed to the outer convolutions of the spiral of a record of the size from which the sound is to be reproduced. The knurled head 39 is then forced inwardly to cause the worm wheel 33 to

engage with the worm 32, and the shaft will be held in that position by the locking pin 42, which will drop into the groove 41 of the shaft 34 when the said shaft 34 is in this inward position. When now the motor 70 is started and the turntable or record support rotated thereby, a gradually increasing speed of rotation will be imparted to the shaft 34 through the pinion 10, gear 28, shaft 29, worm 32 and worm wheel 33, 75 rigidly secured to the shaft 34, and the cam 36, also rigidly secured to the said shaft 34, will be slowly rotated in the direction of the arrow 58 of Fig. 3. This rotation of the cam 36 will slowly carry the free end of 80 the pivoted lever 45 outwardly from the axis of the shaft 34, and correspondingly turn the lever 46 on its pivot on account of the engagement of the lever 45 with the end of the screw 48, thus moving the pad 47 85 inwardly and allowing the disk 46 of the governor to also move inwardly and increase the speed of the motor.

The periphery of the cam 36 is made of such a shape that the rate of the increase 90 in the speed imparted to the motor, and consequently to the record support 16, is substantially inversely proportional to the ratio which the radii of adjacent convolutions of the spiral record groove bear to 95 each other for each revolution of the record support, and consequently as the stylus 55 of the reproducer travels inwardly from the periphery of the record disk toward the center of the disk, the speed will be gradually increased, and the linear speed of the record at the point where it engages the stylus will be maintained constant for any length of record. If, therefore, the linear speed at which the record is recorded be 100 constant at the point of the engagement of the recording stylus with the surface being recorded, the correct variable motion of the turntable for reproducing a record formed from such original record will be obtained 105 by setting the pointer opposite that number of the graduation on the dial which indicates the speed or number of revolutions at which the first convolution of said record was originally recorded. Then by throwing 110 the worm gear 33 into engagement with the worm 32 by pushing the knob 39 inwardly, the speed of rotation of the turn-table or record support will be gradually increased 115 to maintain that point of the record immediately under the stylus at a constant linear speed.

It is of course obvious that were the original record recorded with the beginning of the record at the center of the disk and the 125 end of the record at the periphery of the disk, the cam would be the reverse of the cam shown in the drawings of this application, or the shaft 34 should be geared to rotate in the opposite direction and the angu- 130

lar speed of the record support would be decreased instead of increased, but this reversal of the parts and operation is fully within the aim and scope of my invention and will not depart from my invention above described or vary substantially the operation of the mechanism.

Although in my specification and claims I have termed the record upon which the sound was recorded as a disk record, I employ this term for the purpose of indicating broadly any type of record in which the sounds are recorded in a line, or ridge or groove in spiral form, that is to say one in which the record line, ridge or groove begins either at the outer periphery of the disk and extends in a spiral toward the center of the disk or conversely one in which the record begins at or near the center of the disk and the line, ridge or groove extends outwardly in a spiral form to or near the periphery of the disk and the stylus may be either a recording or a reproducing stylus.

Having thus described my invention, what I claim and desire to protect by Letters Patent of the United States, is:

1. In a talking machine, the combination with a rotary record support, of a variable speed motor therefor, a sound reproducer arm, a sound reproducer mounted on said arm and arranged to coöperate with a sound record on said support, a stationary support for said arm and means movable independently of said arm and actuated by said motor to maintain the speed of said record support substantially constant at a point which is continuously moving transverse to said record support during the revolution of said support.
2. In a talking machine, the combination with a rotary record support, of a variable speed motor for actuating said support, a sound conveyer, a sound reproducer mounted on said conveyer and provided with a stylus and movable across said record support, a stationary support for said sound conveyer and means independent of the said reproducer and of said stationary support and actuated by said motor for varying the speed of said motor to maintain the speed of said record support substantially constant at the point of the engagement of said stylus with a record on said record support as the said reproducer moves across said support.
3. In a talking machine, the combination with a rotary record support, of a variable speed motor therefor, a reproducer arm, a sound reproducer mounted on said arm and arranged to move across and coöperate with a sound record on said record support, a stationary support for said arm and automatic means independent of said reproducer and of said stationary support for varying the speed of said motor to maintain the sur-

face speed of a record on said record support substantially constant at the point of engagement of said reproducer with said record as the reproducer moves across the record.

4. In a talking machine, the combination with a rotary record support, of a variable speed motor therefor, a sound reproducer arm, a sound reproducer mounted on said arm and arranged to move across the face of a sound record arranged upon said record support, a stationary support for said arm and means independent of said reproducer and of said stationary support and automatically actuated independently of the position of said reproducer or said arm to vary the angular velocity of rotation of said record support to maintain the surface speed of a record substantially constant at the point of engagement between said reproducer and said record.

5. In a sound reproducing machine, the combination of a variable speed motor, a support for a disk record, a reproducer arranged to coöperate with said record to be moved across the face of said record during the reproduction of sound therefrom, means independent of the position of said reproducer to vary the speed of said motor to vary the angular velocity of the rotation of said record support to maintain the surface speed of said record support constant at the point of the engagement between said record and said reproducer, and means to disconnect said speed varying means and to adjust the speed of said record support to a fixed angular velocity, to effect constantly changing speed at the point engaged by said reproducer.

6. In a sound reproducing machine, the combination of a variable speed motor, a support for a disk record, a reproducer arm, a reproducer mounted on said arm, and arranged to be progressed by coöoperative engagement with said disk record, a stationary support for said arm and means actuated independently of and movable independently of said reproducer and of said stationary support to automatically vary the speed of said motor during each revolution of said record support inversely proportionally to the relation which the radii of adjacent convolutions of the record bear to each other.

7. In a sound reproducing machine, the combination of a variable speed motor, a support for a disk record, mounted on said arm, and a reproducer arranged to coöperate with a disk record and to be fed across said record by the engagement of said reproducer with said record, a stationary support for said arm and means, actuated independently of the position of said reproducer and of said stationary support, and movable independently of said reproducer to vary the angular velocity of said record support dur-

ing each revolution of said support, inversely proportionally to the relation which the radii of adjacent convolutions of the record groove bear to each other.

5. 8. In a sound reproducing machine, the combination of a variable speed motor, including a governor, a movable sound reproducer, and a rotary cam driven from said motor independently of said sound reproducer and acting on said governor to continuously vary the speed of the rotation of said motor inversely proportionally to the relation which the radii of adjacent convolutions of a record groove of a disk record bear to each other, and a support for a disk record driven by said motor.

9. In a sound reproducing machine, the combination of a motor including a governor, a record support driven by said motor, a disk record carried thereby and a cam driven from said motor and acting on said governor to vary the speed of the rotation of said motor inversely proportionally to the relation which the radii of adjacent convolutions of the record groove of said record bear to each other, a reproducer co-operating with said record, and means to disconnect the driving connection between said cam and said motor, and to adjust the speed of said motor to a constant predetermined speed.

10. In a sound reproducing machine, the combination with a disk record support and a reproducer arm, of a sound reproducer mounted on said arm to move transversely to said record support, a stationary support for said arm, a variable speed motor, and means movable independently of said reproducer and of said stationary support, and operated by said motor, for imparting a constantly varying speed of rotation to said motor and to said record support.

11. In a sound reproducing machine, the combination with a record support and a disk record carried thereby, of an arm pivoted adjacent to said support, a sound reproducer carried by said arm and arranged to co-operate with the record on said support, and to be moved thereby, a motor including a governor, a rotary cam driven by said motor, independently of said arm, and arranged to control the movement of said reproducer through said support, and means controlled by said cam co-operative with said governor to maintain the surface speed of said record support constant at the point of engagement of said reproducer with the groove of said record.

12. In a sound reproducing machine, the combination of a motor, a disk record support driven thereby, a reproducer and a reproducer arm, a rotary cam, by the position of which the speed of said motor is determined, means independent of said reproducer and of said arm to operatively

connect and disconnect said cam with said motor, and means whereby, when said cam is connected to and driven by said motor, the speed of said motor is automatically varied, and when disconnected the speed of said motor is constant.

13. In a sound reproducing machine, the combination of a variable speed motor, a disk record support driven thereby, a reproducer and a reproducer arm, a cam, by the position of which the speed of said motor is determined, means independent of said reproducer and of said arm to operatively connect and disconnect said cam with said motor, and means whereby when said cam is connected to and driven by said motor, the speed of said motor is automatically varied.

14. In a talking machine, the combination with a reproducer, a reproducer arm, and a motor provided with a governor, of a disk record support driven thereby, a lever, one end of which is adapted to co-operate with said governor and by its position to control the speed thereof, a cam rotatable with respect to said lever and co-operative therewith to change the position of the lever to vary the speed of said governor, and means independent of said reproducer and of said reproducer arm to rotate said cam automatically by said motor.

15. In a talking machine, the combination with a reproducer, a reproducer arm and a motor provided with a governor, of a disk record support driven thereby, a lever, a pad on one end of said lever adapted to co-operate with said governor and by its position to control the speed thereof, a cam rotatable with respect to said lever and operatively connected thereto, the rotation of said cam serving to change the position of said pad and consequently varying the speed of said governor, means independent of said reproducer and of said reproducer arm to rotate said cam automatically by said motor, and means to disconnect said cam from its driving connection with said motor.

16. In a talking machine, the combination with a motor provided with a governor, of a disk record support driven thereby, a lever, a pad on one end of said lever adapted to co-operate with said governor and by its position to control the speed thereof, a cam rotatable with respect to said lever and operatively connected thereto the rotation of said cam serving to change the position of said pad and consequently varying the speed of said governor, means to rotate said cam automatically by said motor, and means to disconnect said cam from its driving connection with said motor, said cam being rotatable when thus disconnected to adjust the speed of said motor to a fixed and predetermined rate.

17. In a talking machine, the combination with a motor provided with a governor, of a disk record support driven thereby, a lever, one end of which is adapted to cooperate with said governor and by its position to control the speed thereof, a cam rotatable with respect to said lever and coöperative with said lever to change its position and thereby vary the speed of said governor, and means directly connected with said motor to rotate said cam automatically. 70
18. In a talking machine, the combination with a motor provided with a governor, of a disk record support driven thereby, a lever, a pad on one end of said lever adapted to coöperate with said governor and by its position to control the speed thereof, a rotatable cam operatively connected to said lever and serving to change the position of said pad to vary its frictional engagement with said governor, means positively connected with said motor to rotate said cam automatically, and means to disconnect said cam from its driving connection with said 75 motor. 80
19. In a talking machine, the combination with a motor provided with a governor, of a lever having a friction pad coöperative with said governor to vary the speed thereof, a rotatable cam operatively connected with said lever and arranged to change the position of said friction pad with respect to said governor, means positively connecting said cam with said motor, means to disconnect said cam from its driving connection with said 85 motor, and means operative to manually shift said cam to adjust the speed of said motor to a fixed and predetermined rate. 90
20. In a talking machine, the combination with a variable speed motor, of a record support driven by said motor and arranged to carry a disk record, a reproducer arranged to coöperate with said record, means driven by said motor independently of said reproducer to vary the speed of said motor, and means to disconnect the driving connection between said speed-varying means and said motor, and to adjust the speed of 95 said motor to a constant predetermined speed. 100
21. In a talking machine the combination of a sound reproducer, a reproducer arm, a stationary support therefor, a variable speed motor, a support for a disk record, and means independent of said stationary support and of said reproducer to vary the speed of said motor to maintain the surface speed of said record support substantially constant at a point which is continuously moving transversely to the record support during the revolution of said record support. 115
22. In a talking machine, the combination with a rotary record support, a sound 120 conveyer, a sound reproducer mounted on said conveyer to move in relation to said support, and a stationary support for said conveyer, of a variable speed motor operatively connected with said record support to rotate the same, and automatic means actuated and movable independently of said sound reproducer and said stationary support for varying the speed of said motor to give a constantly varying speed of rotation 125 to said record support. 130
23. In a talking machine, the combination with a rotary record support, of actuating means therefor, and a rotary cam arranged to automatically vary the speed of said actuating means to give said record support a constantly varying speed of rotation, said cam being adjustable independently of said actuating means to vary the initial speed of said actuating means. 135
24. In a talking machine, the combination with a rotary record support, of actuating means therefor, a reproducer, a sound conveyer on which said reproducer is mounted, a stationary support for said conveyer, and a rotary cam automatically rotated by said actuating means independently of said reproducer and said stationary support to vary the speed of rotation of said record support. 140
25. In a talking machine, the combination with a rotary record support, of actuating means therefor, and a rotary cam automatically rotated by said actuating means to vary the speed of rotation of said support, said cam being rotatably adjustable independently of said actuating means to vary the initial speed of said actuating means. 145
26. In a talking machine, the combination with a rotary record support, of actuating means therefor, a rotary cam automatically actuated for varying the speed of said support, a graduated plate and an indicator operatively connected to said cam and co-operating with said plate to indicate the speed of said support. 150
27. In a talking machine, the combination with a rotary record support, of actuating means therefor, a rotary cam automatically actuated for varying the speed of said support, a graduated plate and an indicator operatively connected to said cam and co-operating with said plate to indicate the speed of said support, said cam being rotatably adjustable independently of said actuating means to determine the initial speed of said support. 155
28. In mechanism of the class described, in combination, a record member, means adapted to rotate said member, means adapted to vary the angular velocity thereof, comprising a cam member, a lever having a portion engaging said cam member, a contact member associated with said lever, means adapted to move said cam member, 160

whereby said lever will operate said contact member to act upon said first mentioned means, and means whereby said cam member may be set at given positions to correspond to various sized record members.

29. In a talking machine, the combination with a rotary record support, of a movable sound reproducer arranged to coöperate with a record on said support, a variable speed motor arranged to rotate said support, and means automatically actuated by said motor independently of said reproducer for varying the speed of said motor to give a constantly varying speed of rotation to said support, said means being adjustable to control said motor to produce a constant speed to give said record support a constant speed of rotation.

30. In a talking machine, the combination with a record support, a reproducing mechanism, and a motor arranged and adapted to rotate said record support at a constant angular velocity, of means arranged to be thrown at will into operation to vary the speed of said record support regularly to produce a constant linear speed of said record support under said reproducing mechanism.

31. In a sound reproducing machine, the combination of a motor including a governor, a movable sound reproducer, a support for a disk record driven by said motor, a cam driven by said motor independently of said reproducer and acting on said governor to continuously vary the speed of the rotation of said motor to maintain constant the linear speed of said record on said support at the point where it coöperates with said reproducer.

32. In a sound reproducing machine, the combination with a rotary support adapted to rotate a disk record, an arm pivoted adjacent to said support, a sound reproducer carried by said arm and arranged to co-operate with the record on said support and to be propelled by said record, a motor including a governor, a cam driven by said motor independently of said arm, and means including said cam and coöperating with said governor to maintain the surface speed of said record support constant at the point of engagement of said reproducer with the groove of said record.

33. In a sound reproducing machine, the combination of a motor, a disk record support driven thereby, a sound reproducer and a reproducer arm, a cam and connections between said cam and said motor whereby the speed of said motor is determined by the position of said cam, and means independent of said reproducer and of said arm

to operatively connect and disconnect said cam with said motor whereby when said cam is connected to and driven by said motor the speed of said motor is automatically varied 65 and when disconnected the speed of said motor is constant.

34. In a talking machine, the combination of a motor provided with a governor, of a disk record support driven thereby, a lever 70 to coöperate with said governor and by its position to control the speed of said governor and of said motor, a cam movable with respect to said lever and coöperating therewith to change the position of said lever 75 and to thereby vary the speed of said governor and means directly connected with said motor to move said cam automatically to thereby gradually and continuously vary the speed of said governor.

35. In a mechanism of the class described, in combination, a record member, means adapted to rotate said member, means adapted to vary the angular velocity thereof comprising a cam member, a lever engaging said cam member, means adapted to move said cam member by said first-mentioned means whereby said lever will act upon said first-mentioned means, and means whereby said cam member may be set at different positions to correspond to various sized record members.

36. In a mechanism of the class described, in combination, a turntable, means to rotate said turntable and means to vary the angular velocity thereof, comprising a cam, a lever engaging said cam, means to move said cam automatically by said motor whereby said lever will operate upon said motor to vary the speed thereof and means whereby 100 said cam member may be set at given positions to correspond with various sized record members.

37. In a talking machine, the combination with a rotary record support, of a variable speed motor therefor, a sound reproducer arm, a sound reproducer carried by said arm and arranged to coöperate with the record on said support, and means movable independently of said reproducer and independently of said arm and positively driven by said motor to maintain the speed of said record support substantially constant under said reproducer in its traverse across a record on said record support.

In witness whereof I have hereunto set my hand this 20th day of January A. D., 1910.

BELFORD G. ROYAL.

Witnesses:

HARRY CABLE KENNEDY,
FRANK B. MIDDLETON, Jr.

It is hereby certified that in Letters Patent No. 1,305,745, granted June 3, 1919, upon the application of Belford G. Royal, of Camden, New Jersey, for an improvement in "Talking-Machines," errors appear in the printed specification requiring correction as follows: Page 4, line 34, claim 1, after the word "arm" insert the words *and of said stationary support*; same page, claim 7, strike out lines 121-122 and insert the words *support for a disk record, a reproducer arm, a reproducer mounted on said arm, and arranged to coöperate*; same page and claim, strike out lines 126-130 and insert the words *for said arm and means actuated independently of the position of said reproducer, and movable independently of said reproducer and of said stationary support, to automatically vary the angular velocity of said record support dur-*; and that the said Letters Patent should be read with these corrections therein that the same may conform to the record of the case in the Patent Office.

Signed and sealed this 7th day of October, A. D., 1919.

[SEAL.]

M. H. COULSTON,

Acting Commissioner of Patents.

Cl. 74—45.
